(57) **CLAIM**

The ornamental design for a cutting insert for chip removing machining, as shown and described.

DESCRIPTION

FIG. 1 is a perspective top view of a cutting insert for chip removing machining.

FIG. 2 is a perspective bottom view of the cutting insert for chip removing machining.

FIG. 3 is a top view of the cutting insert for chip removing machining.

FIG. 4 is a side view of the cutting insert for chip removing machining.

FIG. 5 is a front view of the cutting insert for chip removing machining.

FIG. 6 is another side view of the cutting insert for chip removing machining.

FIG. 7 is a bottom view of the cutting insert for chip removing machining; and,

FIG. 8 is a rear view of the cutting insert for chip removing machining.

The broken line showing of the cutting insert is for the purpose of illustrating environmental structure and forms no part of the claimed design.
